UNITED STATES PATENT OFFICE.

HARRY G. MITTELSTAEDT, OF NEW YORK, N. Y.

PRINTING APPARATUS.

1,194,410.

Specification of Letters Patent. Patented Aug. 15, 1916.

Application filed July 24, 1915. Serial No. 41,631.

To all whom it may concern:

Be it known that I, HARRY G. MITTELSTAEDT, citizen of the United States, and resident of Richmond Hill, borough and county of Queens, city and State of New York, have invented a certain new and useful Improvement in Printing Apparatus, of which the following is a specification.

My invention relates to printing apparatus and more particularly to that type thereof which is specially adapted for printing or stamping the usual bank indorsements on the back of checks or other documents.

The object of my improvement is to provide a simple mechanism which will efficiently indorse successive checks without necessitating their individual removal from the printing bed or platen and which within its operative limits will automatically accommodate itself to the gradually increasing pile of checks.

A further object of my invention is to operatively connect the said apparatus with a computing machine of any well known type in such a manner that both mechanisms may be simultaneously operated or each actuated independently of the other.

My invention will be fully described hereinafter and the features of novelty will be pointed out in the appended claims.

In the accompanying drawings which illustrate an example of my invention Figure 1 is a side elevation of my improved apparatus in its normal position; Fig. 2 is a similar view showing the mechanism in operation; Fig. 3 is a plan view; Fig. 4 is a detail section of the printing roller and its carrier; Fig. 5 is a detail side view of said carrier; Fig. 6 is a detail section of the connection between my apparatus and a computing machine, and Fig. 7 is a detail section of another part of the apparatus.

As shown in the illustrated example my apparatus comprises a base 10 which may be constructed of any suitable material and is provided with a printing bed or platen 11 from which a bed plate 12, preferably inclined upwardly, extends toward the rear as shown in Figs. 1 and 2, the rear edge of said bed plate 12 being supported in any suitable manner as by means of an upright

13 secured to the base 10. The platen or printing bed 11 is preferably raised above the base 10, although in some cases said platen may be in surface engagement therewith, it being understood that if desired the said platen may be omitted entirely and the upper surface of the base itself utilized as a printing bed. In any case pins 11^a may project upwardly from the platen 11 or the base 10 for the purpose to be more fully explained farther on in the description. A plate or lever 14 is pivotally connected at 15 with lugs 16 secured to or forming part 65 of the base 10 and in the normal position of the parts occupies an upright position as shown for instance in Fig. 1, said plate or lever 14 being provided on its one face, at intermediate points, with bearings 17. The latter serve as journals for a shaft 18 which carries a frame comprising arms 19 rigidly connected together in any suitable manner as by means of a cross-brace 20 and which at their free ends rotatably carry a shaft 75 21. This shaft 21 carries the printing roller 22 which is provided on its surface with any arrangement of type or the like 23 whereby the desired impression may be made and is preferably detachably connected with said shaft 21 in any suitable manner as by means of a key and groove 24 as shown in Fig. 4. In order that said roller 22 may be removed from the shaft 21, when for any reason this is desired or necessary, I prefer to construct the one arm 19 in two parts, the free end portions 19^a being hinged or pivoted to the main portion by means of a hinge 25. Any suitable means may be provided for locking the portion 19^a in alignment with the main portion of the arm 19 as for instance by providing a recess 26 in one hinge section and cooperating projection 27 on the other hinge section as shown in Fig. 5. With this arrangement the portion 90 19^a may be raised in the hinge member 25 to disengage the recess 26 and projection 27 from each other when it is desired to pivotally swing said portion 19^a to an inoperative position to release one end of the shaft 100 21 and permit the removal of the roller 22. The latter is normally in contact with the bed plate 12 and is maintained in engagement therewith in any desired way as by

means of a coil spring 28 surrounding the shaft 18 and having one end in engagement with the lever 14 or one of the bearings 17 thereof and its other end in engagement 5 with one of the arms 19 as shown in Fig. 3. In order that the type or the like 23 of the printing roller 22 may be properly inked, I provide for instance a rotatable pad 29 carried by an axle 30, the ends of which 10 project through slots 31 in the arms 19, said inking pad being maintained in surface engagement with the printing roller in any suitable manner as by means of springs 32 the tension of which is exerted on the axle 15 30 toward the roller 22. The apparatus further includes a pressure or guide member 33 pivotally secured at 33^b to lugs 34 secured to or forming part of the bed plate 12, said pressure member 33 being cut out 20 to form a space 35 and fingers 33^a, the latter being preferably resilient or elastic for the purpose to be more fully described hereinafter. In the normal condition of the apparatus this pressure member 33 projects in 25 a substantially upright position in engagement with the printing roller 22 and is maintained in and returned to this position for instance by means of a spring 36 having one end in engagement with the bed 30 plate 12 and its other end in contact with said member 33. In order that the roller 22 may be automatically maintained in proper operative position and against unintentional rotation when in its normal position I prefer to provide gear wheels 37 and 37^a the first being rigidly secured to the shaft 21 and the latter being rotatable with said shaft but removable therefrom in order that the printing roller 22 may be disconnected from said shaft as hereinbefore described. These gear wheels 37 and 37^a are arranged in mesh with coöperating racks 38 located in the one surface of the pressure member 33 and preferably terminating at the points where the resilient fingers 33^a begin. In some cases the gear wheel 37^a and its coöperating rack 38 may be omitted while in other cases the gears 45 may be replaced by friction rings of rubber, felt or the like arranged to coöperate with strips of similar material located on the member 33 in place of the racks 38.

At the rear of the plate or lever 14 the base 10 is provided with bearings 39 in which a shaft 40 is journaled, said shaft 40 carrying an upright arm 41 the free end of which is preferably provided with a roller 42 adapted to engage and travel on the rear surface of said lever 14. Any suitable means may be 55 provided for preventing lengthwise movement of the shaft 40 in its bearings as for instance by providing collars 40^a thereon in engagement with the bearings 39. The said shaft 40 further carries a lever 43 60 which has its free end pivotally connected at

44 with a rod or the like 45, the latter extending into a tube 46 having for instance a forked end 47 adapted to be pivotally connected at 48 with the handle 49 of any type of computing machine or other mechanism arranged to be manually actuated by said handle and with which a printing apparatus is adapted to be operatively combined. In order that the rod 45 and tube 46 which have a common major median line, may be operatively coupled together I provide for instance a hook 50 pivoted at 51 upon the tube 46 and having an operating finger piece 52 located in close proximity to the handle 49 of the computing machine. In its operative 70 position this hook 50 extends through a slot 53 in the tube 46 and engages a notch 54 formed in the rod 45 and adapted to register with said slot whereby the rod is operatively connected with said tube 46, a spring 55 being provided for maintaining said hook in and returning it to its operative position. This arrangement further includes a slide 56 mounted on the tube 46 and adapted to be moved over the slot 53 when it is desired to 75 temporarily maintain the hook 50 out of engagement with the notch 54.

As an example of the utility of the apparatus I will describe the operation thereof in combination with what is commonly known 80 as an adding machine. Such adding machine may be set directly on the base 10 between the combined rod and tube 45 and 46 and the printing apparatus and if necessary secured to said base to prevent relative movement 85 between the two machines as units, although usually the weight of the adding machine itself will be found sufficient to firmly anchor it on said base 10. Or the base 10 may be reduced in area and then clamped or 90 otherwise secured to the adding machine itself or to the stand or support which oftentimes forms part of the adding machine equipment. In either case the end of the tube 46 is pivotally secured as at 48 with the 95 handle 49 of the adding machine, it being understood that the slot 53 is uncovered and that the hook 50 is in engagement with the notch 54 so that the rod 45 and tube 46 are 100 operatively coupled together. Assuming 105 now that the operator has before him a number of checks the amounts of which he desires to set up in the adding machine and each of which is to receive the bank's 110 endorsement, said operator after having properly actuated the adding machine keys to set 115 up the total of the first check deposits said check in an inverted condition or face downwardly upon the platens 11 and against the pins 11^a which serve to properly position 120 said check on said platen. The handle 49 of the adding machine is then actuated in the usual manner in the direction of the arrow in Fig. 1 to print the amount of the 125 check which operation exerts a pull on the 130

connected tube 46 and rod 45 and consequently swings the lever 43. This brings about a rocking of the shaft 40 and the arm 41 and causes the roller 42 to exert a pressure on the plate or lever 14 whereby the latter is swung on its pivots 15 to the position shown in Fig. 2. At the same time the printing roller 22 commences to travel downwardly on the bed 12 and said roller 5 or the gear wheels 37 and 37^a thereof exert a pressure on the pressure or guide member 33 which in consequence is swung downwardly on its pivots 33^b against the tension of the spring 36. A continued movement 10 of the handle 49 will cause the gears 37 and 37^a to travel along the racks 38 to further depress the pressure member 33, the resilient fingers 33^a finally engaging the check and clamping it on the platen 11 while the rotating printing roller passes over the space 15 35 and imparts an impression of the type 23 or the like on the back of said checks, the parts now being in the position shown in Fig. 2. During this operation of the parts 20 the spring 28 exerts a pressure on the arms 19 and thus maintains the roller 11 in proper engagement first with the bed 12 and later with the pressure or guide member 33, while 25 the inking pad 29 is maintained in operative engagement with the printing roller 22 by 30 means of the springs 32. It will be understood that the tension of the spring 28 is sufficient to bring the type 23 into firm engagement with the check which is to be indorsed thus bringing about a clear impression. In this manner the printing of the 35 amount of the check and the indorsement thereof is simultaneously accomplished by a complete actuation of the handle 49 which 40 is now started on its return movement. This return movement of said handle 49 exerts a push on the connected tube 46 and rod 45 and consequently swings the lever 43 in the reverse direction and similarly rocks the 45 shaft 40 thus moving the roller 42 of the arm 41 away from the plate or lever 14. As soon as this happens the tension of the spring 36 tending to swing the member 33 from the position shown in Fig. 2 back to 50 its upright position as shown in Fig. 1 will cause said member 33 to exert a back pressure on the roller 22 which in consequence will be forced backward and will therefore, swing the lever 14 back to its initial position 55 as shown in Fig. 1.

It will be understood that the spring 28 assists in imparting an initial rearward movement to the lever 14 and that the tension of said spring 28 is sufficient to prevent the 60 pressure of the member 33 under the influence of the spring 36 from swinging the arms 19 and printing roller 22 upwardly on the shaft 18 so that the elements are readily and efficiently returned to the normal 65 position shown in Fig. 1. During this re-

turn movement the gears 37 and 37^a will again travel along the racks 38 in the reverse direction so that at the finish of the return movement the printing roller 22 will have been rotated back to its original position 70 and will be locked in this position against accidental rotation through the co-operation of the said gears 37 and 37^a and the racks 38. The printing roller 22 is, in this manner, at 75 all times maintained in proper operative relation to the space 35 so that a proper impression on the check is always assured. At the same time the member 33 when in its normal position is entirely removed from the printing bed and thus does not interfere with the 80 manipulation or handling of the checks. As soon as the parts have again reached their normal position the operator sets up the amount of the next succeeding check in the adding machine and then places this second 85 check face downwardly upon the first check whereupon the handle 49 is again actuated in the direction of the arrow in Fig. 1. In this way the amount of said second check is 90 printed in the adding machine and the indorsement is simultaneously impressed on said second check by the printing roller 22. This operation is continued, it being understood 95 that the amount of each succeeding check is first set up in the adding machine after which said check is placed face downwardly upon the preceding check or checks on the platen 11. The pressure member 33 and the flexible fingers 33^a thereof readily accommodate themselves to the increasing 100 pile of checks on the platen 11 and firmly and properly clamp same during the movement of the printing roller 22 over the space 35 so that a legible and extremely clean impression of the indorsement is produced on 105 each check. At the same time the member 33 serves to guide the printing roller 22 to progressively higher planes as the pile of checks on the bed 11 increases in height, so that said roller is at all times positively 110 caused to travel over the uppermost check and leave an impression of the type 23 on the back thereof. It will be seen that, with my improved arrangement it is unnecessary 115 to remove the individual checks from the platen or printing bed before the next succeeding check is placed upon the bed, the checks being simply successively piled one on the other until the limit of the apparatus has been reached after which the entire pile 120 of checks may be removed as a unit. The handling of the checks is thus reduced to a minimum and said checks are at all time readily available to the operator for any purpose. The parts are so proportioned 125 that even when the pile of checks has reached the maximum height which the apparatus will accommodate the indorsement will be completely impressed on some part of the back of each check without requiring each 130

succeeding check to be carefully positioned with respect to the printing mechanism. It will of course, be understood that means other than the pins 11^a may be provided for positioning the checks on the bed 11 if desired. My improved arrangement also does away with the complicated mechanism included in existing machines for carrying the indorsed checks away from the printing bed or platen and at the same time keeps said checks within easy reach of the operator for purposes of comparison or the rectifying of mistakes.

In many adding or computing machines it is necessary to completely actuate the handle 49 or its equivalent twice before the adding machine mechanism is properly operated. Such double operation would ordinarily bring about a double operation of my improved printing apparatus with the consequent double impression and possibility of blurring. If my apparatus is combined with a machine of this type the finger piece 52 which is in close proximity to the handle 49 and thus within easy reach is depressed just prior to the initial actuation of the handle 49 to disengage the hook 50 from the notch 54. If the said handle 49 is now operated the tube 46 will simply slide along the rod 45 without carrying it along so that the adding machine will be operated without bringing about an actuation of the printing mechanism. As the handle 49 is returned after the completion of its initial movement the tube 46 will slide back upon the rod 45 until the end thereof engages the hook 50 and forces it outwardly in the slot 53 it being understood that the pressure on the finger piece 52 has been previously removed. As the return movement of the handle 49 is continued the hook 50 will ride along the rod 45 and will finally snap into the notch 54 under the influence of the spring 55 to automatically again couple the rod 45 and tube 46 together. As the handle 49 is now operated the second time to complete the operation of the adding machine mechanism, the printing apparatus will be simultaneously actuated in the manner hereinbefore described thus producing a single impression on the uppermost check and avoiding the possibility of blurring. It sometimes happens that the operator after having set up the amounts of a given number of checks in the adding machine discovers that a mistake has been made which necessitates a clearing of the adding machine and a complete re-setting up of the correct amounts therein. In such cases, if the checks have all been indorsed it is desirable to actuate the adding machine independently of the printing apparatus until the proper corrections have been made. To provide for this temporary independent operation of the adding machine I have included the slide 56 which may be simply

moved beneath the raised hook 50 to close the slot 53 and thus prevent the said hook 50 from entering the notch 54. In this condition the handle 49 may be actuated as often as necessary and will simply cause the tube 46 to slide on the rod 45 without operating the same so that the printing apparatus remains at rest while the adding machine is freely operated. As soon as the necessary corrections have been made and it is desired to again operatively combine the adding machine and printing apparatus the slide is simply pushed back to uncover the slot 53 and permit the hook 50 to again enter the notch 54. It will, of course, be understood that the movement of the tube 46 relatively to the rod 45 is under no condition great enough to cause a complete separation of the tube and rod, so that these elements are at all times maintained in proper operative relation to each other. It will be further understood that the rod 45 and tube 46 as well as the slide 56 are only examples and that other equivalent devices may be substituted for accomplishing the same or equivalent results. This is also true of the hook 50 and notch 54.

In some cases the operator may forget to place a given check upon the bed 11 or upon the checks previously placed thereon and as a result may find that after the adding machine has been actuated to print the amount of said check that no indorsement has been impressed on this particular check. Under such conditions it is obviously out of the question to again operate the adding machine or to clear the same as this latter operation might necessitate the re-setting up of the amounts of a number of previously indorsed checks. If the operator arrives at such a contingency all that is necessary is to place the said check face downward as hereinbefore described and then to grasp the lever 14 at any convenient point and move it downwardly on its pivots. This will actuate the printing mechanism independently of the arm 41 and its connected parts and consequently will bring about an operation of the printing mechanism independent of the adding machine. If desired the lever 14 may be provided with a suitably located handle to facilitate the independent operation above mentioned. My improvement thus provides a simple arrangement which may be efficiently operated under all conditions with a minimum of effort and without the necessity for any careful manipulation of any part thereof including the checks. In some cases the printing apparatus may be operated entirely as an independent mechanism in which case a handle might be attached to the lever 43 or the handle previously mentioned in connection with the lever 14 might be utilized for this purpose. It will further be apparent that my improved apparatus

might be operatively combined with mechanisms other than adding machines. If desired a suitable cover may be provided for covering and protecting the inking pad 29.

5 Various changes in the specific form shown and described may be made within the scope of the claims without departing from the spirit of my invention.

I claim:

10 1. The combination of an actuating member for manually operating a mechanism, a printing apparatus, a connection between said member and apparatus comprising sections having a common major median line 15 and movable relatively to each other, means for coupling said sections together whereby said member and apparatus may be simultaneously actuated, said means being movable to an inoperative position to permit 20 a relative movement of said sections whereby said member is movable independently of said apparatus, and means whereby said coupling means is automatically returned to its operative position to couple said sections together.

25 2. The combination of an actuating member for manually operating a mechanism, a printing apparatus, a connection between said member and apparatus comprising telescopic sections slidable relatively to each other, means for coupling said sections together whereby said member and apparatus may be simultaneously actuated, said means being movable to an inoperative position to permit 30 a relative movement of said sections whereby said member is movable independently of said apparatus and means for retaining said coupling means in its inoperative position.

35 40 3. A printing apparatus comprising a printing bed on which the sheets to be impressed are adapted to be superimposed, a printing device, means for actuating said device and means for guiding said device 45 to progressively higher planes as the number of sheets on said printing bed increases.

45 50 4. A printing apparatus comprising a printing bed on which the sheets to be impressed are adapted to be superimposed, a printing roller, means for moving said roller across said printing bed, and means for guiding said roller to progressively higher planes as the number of sheets on said printing bed increases and for holding 55 the sheet being printed upon against movement.

50 55 5. A printing apparatus comprising a printing bed on which the sheets to be impressed are adapted to be superimposed, 60 a movable member, a printing roller movably connected with said member, means for actuating said member to move said roller across said printing bed, and a pressure member whereby said sheets are held against 65 movement during the printing operation and

said roller is guided to progressively higher planes as the number of sheets on said printing bed increases.

6. A printing apparatus comprising a base, a printing bed thereon on which the sheets to be impressed are adapted to be superimposed, a member pivotally mounted on said base, a support pivotally connected with said member, a printing roller journaled on said support, means for swinging 75 said member on its pivot to move said printing roller across said printing bed, and a pressure member whereby said sheets are held against movement during the printing operation and said roller is guided to progressively higher planes as the number of sheets on said printing bed increases.

7. A printing apparatus comprising a base, a printing bed thereon on which the sheets to be impressed are adapted to be superimposed, 80 a member pivotally mounted on said base, a support pivotally connected with said member, a printing roller journaled on said support, an inking pad on said support, means for maintaining said pad in surface engagement with said roller, means for swinging said member on its pivot to move said printing roller across said printing bed, a pressure member whereby said sheets are held against movement 85 during the printing operation and said printing roller is guided to progressively higher planes as the number of sheets on said printing bed increases and coöperating means on said pressure member and roller 90 whereby rotation of the latter in its normal position is prevented.

8. A printing apparatus comprising a base, a printing bed thereon on which the sheets to be impressed are adapted to be superimposed, 105 a member pivotally mounted on said base, a support pivotally connected with said member, a printing roller journaled on said support, an inking pad on said support, means for maintaining said pad in surface engagement with said roller, 110

a shaft journaled on said base, an arm carried by said shaft and having its end in engagement with a surface of said pivoted member, means for rocking said shaft and arm to swing said member on its pivot in one direction and move said roller across said printing bed, a pivoted guide member whereby said roller is guided to progressively higher planes as the number of sheets 120 on said printing bed increases, resilient fingers whereby sheets are held against movement during the printing operation, a rack on said guide member, a pinion connected with said roller and arranged to mesh with 125 said rack and a spring for swinging said guide member in a backward direction whereby said printing roller and pivoted member are returned to normal position, and said pinion and rack are held in opera- 130

tive engagement to prevent a rotation of said roller when in its position of rest.

9. A printing apparatus comprising a printing bed, a lever, a printing roller, a pivoted arm operatively connected with said roller and adapted to move independently of said lever and to operatively move said roller across said printing bed, means for moving said lever in one direction to

cause it to bear against the arm whereby the latter is actuated and for moving said lever in the opposite direction away from said arm and means for causing said arm to follow the latter movement of said lever.

In testimony whereof, I have hereunto set my hand.

HARRY G. MITTELSTAEDT.
